UNITED STATES PATENT OFFICE.

ARTHUR C. KOOTZ, OF MILWAUKEE, WISCONSIN, ASSIGNOR TO THE GEM HAMMOCK & FLY NET COMPANY, OF MILWAUKEE, WISCONSIN, A CORPORATION OF WISCONSIN.

MOP.

Application filed June 4, 1924. Serial No. 717,768.

The invention relates to mops for cleaning or polishing floors, walls, etc., and more particularly to that type of mop in which a fringe of absorbent strands, either dry or 5 saturated with a suitable oil, is used as a cleaning, polishing or dust-absorbing medium.

In many of the mops of this character heretofore proposed, it has been difficult to 10 firmly secure the mop material to the head and at the same time permit of a ready removal of said material, and in some instances where the mop material has been removable the same could only be washed with 15 difficulty because of the construction of the part to which the mop material was secured. The most important object of this invention is to provide a mop in which the mop material is readily attached to or detached 20 from the frame or head of the mop, and which when detached is in the form of a longitudinally-extending relatively flat strip that may be easily washed and put through a wringer.

25 A further object of the invention is to provide a mop in which the mop material may be manufactured at a low cost, and which may be applied to various forms and constructions of mop heads or frames.

30 A further object of the invention is to provide a mopping element for attachment to a mop head in which the mop strands are stitched or otherwise suitably secured to the fabric body, which body has top and 35 bottom passages extending lengthwise thereof for the full length of the body to receive draw-strings or other suitable binding means whereby the mopping element may be quickly and readily secured to the head 40 without danger of coming loose.

The invention further consists in the several features hereinafter set forth and more particularly defined by claims at the conclusion hereof.

45 In the drawings: Fig. 1 is a plan view of a mop embodying the invention;

Fig. 2 is a section taken on the line 2—2 of Fig. 1, with parts of the handle socket broken away;

50 Fig. 3 is a view of the mop and its frame partly assembled, parts being shown in section;

Fig. 4 is a flat view of the mopping element, parts being broken away to show the 55 construction;

Fig. 5 is a section taken on the line 5—5 of Fig. 4;

Figs. 6, 7, and 8 show plan views of mop heads of varying contour to which the mopping element may be applied;

60 Figs. 9, 10, and 11 show sectional views through mop heads of different cross-sections, that may be used in connection with the mopping element, said sections being taken along the line 9—9 of Fig. 6, though 65 not necessarily limited to the outlined construction of said Fig. 6;

Fig. 12 is a plan view of another form of head, more particularly of the skeleton type, to which the mop element may be secured;

70 Fig. 13 is a detail sectional view taken on the line 13—13 of Fig. 13.

The mopping element is made in the form of a flat strip whose ends may be brought together about the head of the mop to form 75 a band. The element includes a fabric body portion, here shown as formed by an inside fabric strip 14 and an outside fabric strip 15 to which the strands of yarn or other suitable absorbent material 16 are secured 80 by stitching through said fabric and strands. In addition, the outer fabric strip 15 is so formed as to provide a longitudinally-extending pocket 17 formed between its sides and the strands, and on what may be termed 85 the top of the strip, and said strip 15 is also folded over at its other end portion 18 to form a longitudinally extending pocket 19 at what may be termed the bottom side of the strip. These pockets are provided to 90 receive binding means or draw-strings 20 and 21. In making a mopping element of this kind the pockets 17 and 19 are formed during the stitching of the fabric strips to the 95 yarn and together, and the draw-strings 20 and 21 are inserted during the same stitching operation, that is, the draw-strings are put into place longitudinally of the mopping element under construction before the strip 15 is folded over to form the pockets, so that 100 on the completion of the stitching operation the draw-strings are in place. This reduces the cost of manufacture materially as the construction obviates the necessity of drawing the draw-strings through after the other parts are stitched together.

105 To provide a finished appearance for the ends of the strip the inner fabric strip 14 may have its ends project beyond the ends of the outer strip and be folded back, as at 110

22, and stitched to the outer strip and to the inner portion of the strip 14, and the yarn 16 during the same stitching operation previously referred to. The result is the 5 formation of a mop element having a longitudinally extending fabric body portion from which the absorbent strands 16 hang, with draw-string pockets formed between parts of the body portion at points so separated from each other that said strip may 10 be bound in the form of a band to the periphery of a mop head or frame by tightening the draw-strings on opposite sides of the frame, whereby the band forms a channel receiving within it the outer edge portion of the head of the mop.

20 The mop head used in conjunction with the mopping element is preferably of triangular shape because of advantages long recognized by the art, to wit: efficient use in corners and under furniture which would be difficult of access with a circular or rectangular-shaped head. The handle is also 25 preferably pivotally connected with the head so that the mop may be readily used under furniture or in those places where an angular disposition of the head relative to the handle is desired.

30 In Figs. 6, 7 and 8 I have shown triangular-shaped heads; in Fig. 6 the corners of the head are rounded off, as at 23; in Fig. 7 the corners are flattened off, as at 24; while in Fig. 8 the plan view of the head shows the relatively sharp corners 24'.

35 The head may consist of a single plate or sheet metal stamping in the form of a flat plate 25, as shown in Fig. 11, or a plate 26 having a down-turned straight flange portion 27, as shown in Fig. 10, or a plate 28 having a down-turned inwardly-curved flange 29, as shown in Fig. 9, the contour of 40 such plates being of any of the forms shown in Figs. 6, 7 and 8.

45 As a means of attaching the socket member 30 the plate forming the head may have, in each instance, ears 31 stamped upwardly therefrom and provided with openings 32 to take the pivot pin 33 which receives the spaced ears 34 of the handle socket 30. The 50 socket member 30 is preferably a sheet metal stamping formed with the ears as above stated and with a cylindrical portion 35 to receive the handle 36 which is clamped thereto by ears 37 on the opposite sides of the cylindrical portion of the socket carrying a clamping screw or bolt 38.

55 In place of a single plate two plates may be used as a head member, as shown in Patent No. 1,158,846, to D. T. Punch, dated November 2, 1915, with the upper plate provided with ears similar to the ears 31 to take the socket member.

60 Instead of a plate forming what might be termed a solid head or frame, a skeleton type of head may be used, as shown in Figs.

12 and 13, in which a bar or rod is bent to form a triangular-shaped frame 39 with the ends of the rod 40 secured together as by a rivet 41 and having members extending inwardly and secured to a clip 42 by a rivet 70 43, said clip providing ears similar to the ears 31 and having apertures 44 to take the pin 33 for the socket member.

75 In each instance the mopping element is secured to the head by positioning it around the head with its medial portion engaging against the periphery of the head and with its free ends brought together, preferably at one side of the head and preferably at that side of the head opposite the apex of the head, and then by drawing up and tightening and tying the draw-strings together on both sides of the head the mopping element is formed into a band overlying both 80 sides of the head with its ends respectively bound together on opposite sides of the head, thereby pocketing the marginal or outer edge portion of the head in a marginal channel, as shown in Fig. 2.

85 It will be understood that the width of the band may vary in order to overlie a greater or less portion of the sides of the head, either at the top or bottom, but the narrower band requires less material and is 90 hence preferred.

95 It will be noted that upon untying the draw-strings the band can be taken off the head and easily washed and put through a wringer in a flat condition.

100 It will also be noted that by the construction above described no laborious threading-through operation is necessary in securing the mopping element to the head, and that when the mopping element is mounted on the head it is firmly bound thereto and will 105 not readily slip along the outer edge of the head.

Attention is also called to the fact that as the upper portions of the mop fringe are 110 positioned adjacent the outer periphery of the head, they form a buffer which prevents any possible injury to furniture by contact of the mop therewith.

115 In Fig. 3 I have shown the lower edge of the mopping element held in position, while in Figs. 1 and 2 I have shown the mopping element assembled to the head by the binding of it through the use of the draw-strings, whose ends project beyond the 120 pockets and are tied together. While the draw-strings 20 and 21 are preferably cords of suitable strength and length, I desire it to be understood that these draw-strings or binding members may be made of other material, such as flexible wire and some of the 125 advantages of my invention obtained, though the use of a flexible cord permits of rapid attachment and detachment of the mop head by the ordinary user.

130 I desire it to be understood that this in-

vention is not to be limited to any particular form or arrangement of parts except in so far as such limitations are specified in the claims or necessitated by the prior art.

6. What I claim as my invention is:

1. In a mop, a mopping element comprising an elongated fabric body provided with spaced upper and lower binding-member-receiving pockets formed therein and extending lengthwise thereof, and strands of absorbent mopping material secured to said body portion and projecting from one edge thereof.

10. 2. In a mop, the combination with a head, of a mopping element having a band surrounding the head and overlapping the top and bottom sides thereof and provided with lengthwise-extending loop portions, and members disposed within said loop portions 20 of the band to respectively draw the top and bottom sides of the band together on the top and bottom sides of the head.

3. In a mop, a mopping element comprising

ing inner and outer strips of fabric, strands of mop material having portions disposed between said strips and secured thereto, said outer strip being folded and secured to the inner strip to form spaced draw-string-receiving passages.

15. 4. In a mop, a mopping element comprising an inner fabric strip, an outer fabric strip and a plurality of strands of absorbent material having portions disposed between said strips and stitched thereto, the outer strip having a longitudinally-extending fold 30 above the upper edge of the mop material to form a draw-string passage at the upper edge of the mopping element, said outer strip having its lower edge folded back and stitched to an adjacent portion of said strip 35 to form a longitudinally-extending draw-string passage at its lower edge.

20. In testimony whereof, I affix my signature.

ARTHUR C. KOOTZ.
